UNITED STATES PATENT OFFICE.

ISAAC E. PALMER, OF MIDDLETOWN, CONNECTICUT.

HAMMOCK-SUPPORT.

SPECIFICATION forming part of Letters Patent No. 691,070, dated January 14, 1902.

Application filed August 18, 1898. Serial No. 688,871. (No model.)

To all whom it may concern:

Be it known that I, ISAAC E. PALMER, a citizen of the United States, and a resident of Middletown, in the county of Middlesex and State of Connecticut, have invented a new and useful Improvement in Hammock-Supports, of which the following is a specification.

My invention relates to an improvement in hammock-supports, and more particularly to a hammock-support in which the backbone or ridge-pole is made extensible, so that it may be compactly packed for shipment and when set up for use may be extended to a greater or lesser extent to suit the wish of the occupant of the hammock supported by it.

A practical embodiment of my invention is represented in the accompanying drawings, in which—

Figure 1 is a view in side elevation of the backbone and upper portions of the supporting-legs, showing the backbone in its contracted closed adjustment. Fig. 2 is a similar view showing the backbone extended. Fig. 3 is an end view, and Fig. 4 is a transverse section along the line 4-4 of Fig. 1 on an enlarged scale.

The legs (denoted by A) may be of any well-known or approved form and may be attached to the ridge-pole or backbone, so as to fold in a manner quite similar to that shown, described, and claimed in my pending application, Serial No. 679,179, filed on April 29, 1898. Their specific structure forms no part of my present invention.

The ridge-pole or backbone is made in the present instance in three sections, the central section being denoted by B and the end sections by B' B². The end sections B' B² are preferably each formed of separate strips, (denoted by b b'), spread apart at the end where the leg is attached and brought together at the opposite end, where they are clamped to the central section B.

A clamping device for holding the parts b' of the end section snugly together and clamping the end section as a whole snugly to the central section B in the desired extended adjustment is constructed as follows: A pair of cheek-pieces (denoted by C C') are fitted to embrace the opposite sides of the section B and the opposite sides of the end section B' or B², and at their lower ends are brought to-

ward one another, as shown at c c', to partially embrace the under side of the end section. The parts b b' are fixed in position between the lower ends of the cheek-pieces C C' by means of bolts c² c³, which extend through the cheek-pieces and through the parts b b', respectively. In the upper ends of the cheek-pieces C C' there is eccentrically pivoted a cam D, provided with an operating-handle d. On the cylindrical portion of the cam D, intermediate of the cheek-pieces C C', a shoe or shoes—in the present instance shoes E E'—are loosely mounted, the lower faces e e' of the said shoes being extended lengthwise of the ridge-pole B, so as to secure an extended and firm grip upon the ridge-pole to hold it in position. The adjustment of the shoes E E' with respect to the upper face of the end B' is such that when the handle d of the cam is elevated the end B', together with the cheek-pieces, cam, and shoes, may be slid freely outwardly and inwardly along the ridge-pole section B and when the desired adjustment is reached the end piece may be locked firmly to the ridge-pole by simply depressing the handle d, thereby rocking the cam D in a direction to depress the shoes E E' into firm gripping contact with the ridge-pole section B, pinching it firmly between the upper face of the section B' and the shoes. To further steady the end sections in their adjustments, I provide guide-pieces F F', arranged to embrace the opposite sides of the part b of the end piece and a portion of the under side of said part, the said pieces F F', being secured to the opposite sides of the ridge-pole section B by a bolt or rivet f. The explanation of the means for clamping the end B' in the desired adjustment with respect to the ridge-pole section B applies equally well to the means for clamping the end B² in the desired adjustment with respect to the said ridge-pole section.

To provide for sustaining the awning in an extended adjustment, I provide arms G G', hinged one at each end of the ridge-pole section B and arranged to fold over into the position (shown in Fig. 1) when the ridge-pole is in its contracted position and out into the position (shown in Fig. 2) when in its extended adjustment. The ends of the arms G G' are conveniently provided with socket-pieces

g g' for slipping over the ends of the arms and holding the end spreaders *H H'* of the awning.

It will be observed that the extension of the ends may be any desired extent within the limits of their length from the contracted position (shown in Fig. 1) to the extended position, (shown in Fig. 2,) and that the parts may be shipped in assembled adjustment, so as to be set up by the most unskilled as well as the skilled, and that it requires but a moment's time to lock the parts in the desired extended adjustment or to shift them to a more or less extended adjustment.

15 What I claim is—

1. The combination with suitable supporting-legs and a backbone formed in sections, one of said sections being formed of spaced bars, of a clamp provided with a cam for lock-

ing the sections together and a guide partially embracing one of the bars of the spaced-bar section and connected with the adjacent section for holding the parts in the desired relation to one another, substantially as set forth.

2. The combination with the extensible backbone, of a folding awning-support hinged to the backbone and arranged to swing from its extended adjustment over into a folded position alongside the backbone, substantially as set forth.

In testimony that I claim the foregoing as my invention I have signed my name in presence of two witnesses.

ISAAC E. PALMER.
